Patented Aug. 11, 1970

218,280

CASTER FOR FURNITURE AND SMALL TRANSPORT DEVICES OR THE LIKE

Walter Schindler, Basel, Switzerland, assignor to Giroflex-Entwicklungs AG, Koblenz, Switzerland, a Swiss corporation

Filed June 21, 1968, Ser. No. 12,465

Claims priority, application Switzerland Feb. 27, 1968

Term of patent 14 years

Int. Cl. D8—03

U.S. Cl. D8—226

FIG. 1

FIG. 2

FIG. 3

FIG. 4

FIG. 5

FIG. 6

FIG. 1 is a perspective view of the caster embodying my new design;

FIG. 2 is a side view thereof;

FIG. 3 is a front view thereof;

FIG. 4 is a rear view thereof;

FIG. 5 is a bottom plan view thereof; and

FIG. 6 is a top plan view thereof.

The undisclosed remaining side of the caster is the mirror-image of the side shown in FIG. 2.

I claim:

The ornamental design for a caster for furniture and small transport devices or the like, substantially as shown and described.
